ROBERT SUCZEK, OF PHILADELPHIA, PENNSYLVANIA, ASSIGNOR TO C. H. WHEELER
MANUFACTURING COMPANY, OF PHILADELPHIA, PENNSYLVANIA, A CORPOR-
ATION OF PENNSYLVANIA.

METHOD OF AND APPARATUS FOR COMPRESSING FLUID.

1,344,967.

Specification of Letters Patent. Patented June 29, 1920.

Application filed March 3, 1917. Serial No. 152,294.

To all whom it may concern:

Be it known that I, ROBERT SUCZEK, a subject of the Emperor of Austria-Hungary, residing in the city of Philadelphia, county 5 of Philadelphia and State of Pennsylvania, have invented certain new and useful Improvements in Methods of and Apparatus for Compressing Fluid, of which the following is a specification.

10 My invention relates to a method of and apparatus for compressing elastic fluid, such as air, gas, vapor, or a mixture of them, and involves the ejector principle in accordance with which a motive fluid entrains the fluid 15 to be compressed, and after entrainment diminishes in velocity while rising in pressure.

It is the object of my invention to provide elastic fluid compressing apparatus operating upon the aforesaid ejector principle, whereby the efficiency shall be materially improved by employment of a plurality of nozzles coöperating with a diffuser common to them, the nozzles producing closely adjacent parallel or intersecting jets of motive fluid, which may be in the form of sheets and which are preferably stepped or overlapped, the fluid to be compressed being delivered toward the motive fluid jets in the 30 form of a jet or sheet, all the jets being delivered into the diffuser, which is suitably aligned or positioned with respect to the nozzles.

And my invention resides in a method of compressing elastic fluid by motive fluid, the latter taking the form of a plurality of closely adjacent parallel or intersecting jets or sheets, the latter preferably stepped or overlapped with respect to each other as regards their longitudinal movement, the elastic fluid to be compressed being admitted in a sheet or jet superimposed upon the motive fluid jets and entrained thereby, the mixture diminishing in velocity and increasing in pressure; and by preference the jet or sheet of elastic fluid to be compressed is isolated from one side of the motive fluid mass, a jet or sheet of which latter is directed along or closely adjacent to a wall of 50 the diffuser.

For an illustration of some of the forms my apparatus may take, and for an understanding of my method, reference may be

had to the accompanying drawings, in which:

55

Figure 1 is a longitudinal cross sectional view of one form my apparatus may take.

Fig. 2 is a longitudinal sectional view through double stage ejector apparatus comprising ejectors of similar character connected in series.

Fig. 3 is a longitudinal cross sectional view, on enlarged scale, of nozzle structure and adjuncts embodying my invention.

Fig. 4 is a longitudinal sectional view of a modified form of the apparatus.

Fig. 5 is a fragmentary cross sectional view of a discharge casing with adjuncts, for any of the types of apparatus herein described, and for general application 70 wherever suitable, wherever condensing water is admitted.

Fig. 6 is a fragmentary cross sectional view taken at right angles to Fig. 5.

Referring to Fig. 1, there is illustrated 75 single stage ejector apparatus in which B and B¹ are circular or annular nozzle passages for the motive fluid, which if elastic, as in the case of steam, is expanded therein. The nozzle passage B is formed between the 80 wall or nozzle member w and the circular nozzle member C₁, and the passage B₁ is formed by the member C₁ and the circular nozzle member C. The member C is disposed upon the end of the stem c screw 85 threaded at s through a wall of the air inlet chamber A₁, rotation of the stem c causing adjustment of the nozzle member C to the right or left. The coöperating nozzle member C₁ is disposed upon a stem c₁ 90 screw threaded at s₁ through a wall of the steam inlet chamber A, rotation of the stem c₁ serving for adjustment of the member C₁ to the right or left. The stem c₁ is hollow, at least at the end adjacent the member C₁, 95 and has a plurality of ports p communicating with the steam inlet A, these ports preferably being of ample area so that there shall exist within the stem c₁ steam pressure substantially equal to that in the steam inlet chamber A. The stem c₁ is supported in the guide g supported by a plurality of circumferentially spaced ribs r, the space between the ribs being at least great enough

so that there shall exist to the left of them 100 a steam pressure substantially equal to that 105

in the steam inlet chamber A. Between the member C₁ and the member w is the annular throat T₁ of the nozzle B. At its center the member C₁ has the throat T for the nozzle 5 B₁, the nozzle member C having a projection t extending toward or into the throat T.

Common to the nozzles B and B₁ is the annular diffuser comprising the side wall members H and H₁, of which the latter is 10 shown straight, as indicated, and wall H is inclined, as shown, the diffuser having a throat at t₂. The diffuser delivers into the discharge casing F which has the discharge outlet F₁. The diffuser wall H may be integral with or suitably joined to the air inlet chamber A₁, which by its flange f may be connected directly or indirectly through suitable connections to the chamber, as a steam condenser, from which the compressible fluid, as air or vapor, is to be removed or in which a high vacuum is to be maintained. The air inlet chamber A₁ communicates at the left of the nozzles B and B₁ with the common diffuser.

25 While the nozzles B and B₁ are adjustable independently of each other by the stems e and e₁, the cross sectional area of the diffuser may also be changed, as by inserting or removing one or more of gas-kets h.

The mode of operation is as follows:

With steam at any suitable or desired pressure delivered to the common steam inlet chamber A, steam passes at the same 35 pressure through throats T₁ and T into their respective expansion nozzles B and B₁, in and by which it is expanded in jets in the form of sheets moving substantially, radially outward, in the example illustrated, 40 the sheet from the nozzle B passing along the inner wall of the diffuser member H₁, and the sheet from the nozzle B₁ passing in a substantially parallel plane or direction, though it may be more or less conical, as 45 indicated, and therefore intersect the sheet from the nozzle B, these sheets combining in the common diffuser. The jet or sheet from nozzle B₁ overlaps or is stepped with respect to the jet or sheet from nozzle B 50 as regards the longitudinal outward progress of the jets, since the outlet end or mouth of the nozzle B₁ is located at a distance from the outlet or mouth of the nozzle B, that is, the closely adjacent nozzles 55 are, in the example illustrated, of different diameters.

Similarly, the air or elastic fluid to be compressed is drawn in a jet or sheet from a nozzle-like structure whose throat is indicated at the region t₃ in communication with the air inlet chamber A₁. The air jet or sheet is in effect superimposed upon the motive fluid jets and is entrained by the latter, the resultant mixture of air and 65 motive fluid advancing through the con-

verging portion of the common diffuser H, H₁ to its throat t₂, with resultant increase in pressure attained at the expense of loss of velocity. The mixture is then discharged into the casing F and delivered at atmospheric pressure or any other desired pressure through the outlet F.

By the construction illustrated, the air inlet is on one side of the diffuser, while the motive fluid inlet is on the other, and the motive fluid jets are formed between the two, the structure affording a uni-lateral admission of the air to the motive fluid jets, since the jet from the nozzle B passes along the wall H₁ of the diffuser, and accordingly no air is admitted to the motive fluid jets from that side.

85 The auxiliary jet from the nozzle B₁ is preferably relatively longer than the main jet from nozzle B, giving longer time, and therefore requiring less energy, to accelerate the incoming air to suitably high velocity before coming into entraining relation with the main jet from nozzle B. Furthermore, while attaining such preliminary acceleration of the air, there is available, however, for the final compression a relatively short non-dispersing highly penetrating jet from the nozzle B.

90 In Fig. 2 two apparatus of the general character illustrated in Fig. 1 are shown connected in series for double stage operation, whereby operation is possible at high total ratio of compression, as for example in excess of 60. And in such double stage 100 arrangement the ratios of compression in the different stages may be made equal or unequal as desired as by making the ratio of compression in the first stage equal to the ratio of compression in the second, or by 105 making it less or greater.

110 It will be understood, however, that the ejector apparatus of either one of the stages may be of a different type than herein disclosed, and may be of any suitable type in which the motive fluid is elastic or a liquid, as water.

There is illustrated in Fig. 2 further structure which is also available in connection with that shown in Figs. 1 and 4, comprising the annular air conducting member D, the opening in which decreases in cross section from the air inlet chamber A₁ toward the steam jets. This member may be adjusted toward the right or the left by 120 suitably withdrawing one and advancing the other. By such adjustment the cross sectional area of the annular air throat at t₃ may be adjusted to suit various operating 125 conditions.

130 The discharge outlet F₁ of the upper or first stage delivers into the intake chamber A₂ of the second stage, the mixture of air and motive fluid then being operated upon

in the second stage, as described in connection with Fig. 1, and raised in pressure and delivered to the discharge casing F_2 , which has the discharge outlet F_3 to atmospheric pressure or any other desired pressure.

In both Figs. 1 and 2 the nozzles B are of larger diameter or longer than the nozzles B_1 ; and it is preferred that the thickness of the jet from the nozzle B shall exceed that from the nozzle B_1 .

In Fig. 3 is shown a structure similar to those hereinbefore described, in that the nozzles all discharge into the common diffuser H_2 . Here again the nozzle members are indicated at C and C_1 , the motive fluid being delivered to the passages I and I_1 from a common steam inlet as before, if desired, while the air or fluid to be compressed is drawn in through the passage I_2 .

In this structure the nozzle members C and C_1 differ in their diameters to greater extent. And while my invention is not limited thereto, in this structure the annular diffuser H_2 is to some extent conical and in alignment with the nozzles.

In Fig. 4 is shown a single stage apparatus of the same general character in which the nozzles B and B_1 are of substantially the same diameters or lengths, and the jets produced thereby are substantially equal in thickness. And in this case both walls H and H_1 of the diffuser are inclined, the steam inlet A in this instance being at the left and the air inlet A_1 at the right.

As illustrated in Figs. 5 and 6, there may be disposed upon the discharge casing F of any of the ejector apparatus herein disclosed, or any other type of ejector apparatus having similar discharge casing, an annular or circumferentially extending chamber E into which water or other suitable cooling liquid is delivered through one or more passages G . Communicating with the chamber E is a circumferential series of injection nozzles n through which cooling liquid is delivered into the casing F , where it operates upon the motive fluid, as steam, to condense the same, the latent heat of the steam serving to raise the temperature of the water which may be utilized for any suitable purpose, as for example, the feed water of a steam boiler.

It will be understood that the proportions of the various nozzles, diffuser, etc., of my apparatus will be varied separately or collectively to suit various operating conditions.

By the method and structure of the character herein described, elastic fluid may be compressed in a single stage apparatus to a pressure whose ratio to the pressure of the fluid before compression is 30 or more; and in double stage the ratio of compression attainable is 60 and higher.

The method and apparatus may be em-

ployed for removing air from a steam condenser; in connection with a refrigerating system operating on the vacuum principle, for producing high vacuum corresponding to the desired temperature of brine or cooling liquid; or for any other purpose.

The elastic fluid, as air, may be raised from atmospheric pressure to suitably higher pressure; or from low absolute pressure, as of 2 inches or less, referred to a 30 inch mercury barometer, to any suitable higher pressure, as atmospheric pressure or higher.

For motive fluid there may be used water or other suitable liquid; or steam or any other suitable elastic motive fluid, as air, vapor, or gas, or a mixture of them, under suitable pressure. And where steam is employed as the motive fluid, it may be live steam of any suitable pressure; or it may be exhaust steam from engines, turbines, etc., which may be of a pressure even below atmospheric.

What I claim is:

1. The method of compressing elastic fluid in a single stage, which consists in producing a motive fluid jet, entraining elastic fluid thereby, producing a second motive fluid jet closely adjacent to said first named jet and separated from the elastic fluid by 95 said first named jet, and increasing the pressure of the mixture by decreasing its velocity.

2. The method of compressing elastic fluid in a single stage, which consists in producing closely adjacent motive fluid jets overlapping each other in the direction of their flow, entraining the elastic fluid in the surface of one of said jets free from the other jet, said one of said jets lying between the 100 elastic fluid and the other motive fluid jet, and increasing the pressure of the mixture by decreasing its velocity.

3. The method of compressing elastic fluid in a single stage, which consists in producing a jet of elastic motive fluid in the form of a thin sheet, entraining thereby elastic fluid to be compressed, producing a second jet of elastic motive fluid in the form of a thin sheet overlying said first named 115 jet and separated thereby from said elastic fluid, and increasing the pressure of the mixture in sheet form by decreasing its velocity.

4. The method of compressing elastic 120 fluid in a single stage, which consists in producing a jet of elastic motive fluid in the form of a thin sheet, entraining thereby elastic fluid to be compressed, producing a second jet of elastic motive fluid in the form 125 of a thin sheet superimposed upon and overlapping said first jet in the direction of their flow, and increasing the pressure of the mixture in sheet form by decreasing its velocity.

5. The method of compressing elastic fluid in a single stage, which consists in producing superimposed jets of elastic motive fluid in the form of thin sheets overlapping each other in the direction of their flow, entraining the elastic fluid to be compressed in one of said jets free from the other jet, said one of said jets lying between the elastic fluid and the other motive fluid jet, and increasing the pressure of the mixture by decreasing its velocity.

6. The method of compressing elastic fluid in a single stage, which consists in expanding elastic motive fluid in a jet flowing along a wall and in contact therewith, superimposing upon said jet a second jet of elastic motive fluid, entraining the elastic fluid to be compressed in said second jet which separates the elastic motive fluid from said first named jet, and increasing the pressure of the mixture by decreasing its velocity.

7. The method of compressing elastic fluid in a single stage, which consists in expanding elastic motive fluid in a jet flowing along a wall and in contact therewith, superimposing upon said jet a second jet of elastic motive fluid overlapping said first named jet in the direction of its flow, entraining the elastic fluid to be compressed in said second jet which separates the elastic motive fluid from said first named jet, and increasing the pressure of the mixture by decreasing its velocity.

8. The method of compressing elastic fluid in a single stage, which consists in expanding elastic motive fluid along a wall in a jet in the form of a disk, superimposing upon said jet a second jet of elastic motive fluid in the form of a disk, entraining elastic motive fluid to be compressed in said second jet which lies between said first named jet and said elastic fluid to be compressed, and increasing the pressure of the mixture by decreasing its velocity.

45 9. The method of compressing elastic fluid in a single stage, which consists in expanding elastic motive fluid along a wall in a jet in the form of a disk, superimposing upon said jet a second jet of elastic motive fluid in the form of a disk overlapping said first named jet in the direction of their flow, entraining elastic motive fluid to be compressed in said second jet which lies between said first named jet and said elastic fluid to be compressed, and increasing the pressure of the mixture by decreasing its velocity.

10. The method of compressing elastic fluid in a single stage, which consists in producing closely adjacent motive fluid jets overlapping each other in the direction of their flow, entraining the elastic fluid in the surface of one of said jets free from the other jet, said one of said jets lying between the elastic fluid and the other motive fluid

jet, said other jet having a thickness greater than said one jet, and increasing the pressure of the mixture by decreasing its velocity.

11. The method of compressing elastic fluid in a single stage, which consists in producing superimposed motive fluid jets in the form of sheets overlapping each other in the direction of their flow, entraining the elastic fluid in the surface of one of said jets free from the other jet, said one of said jets lying between the elastic fluid to be compressed and the other motive fluid jet, said other motive fluid jet being thicker than said one jet, and increasing the pressure of the mixture by decreasing its velocity.

12. The method of compressing elastic fluid in a single stage, which consists in producing superimposed jets of motive fluid in the form of disks, one of said jets having part of its surface isolated from the elastic fluid to be compressed and between which fluid to be compressed and said one of said jets another of said jets is interposed, admitting the elastic fluid to be compressed in a jet superimposed upon said motive fluid jets, and increasing the pressure of the mixture by decreasing its velocity.

13. The method of compressing elastic fluid in a single stage, which consists in producing superimposed jets of motive fluid overlapping each other in the direction of their flow, one of said jets having part of its surface isolated from the elastic fluid and between which and said one of said jets of motive fluid another of said jets of motive fluid is interposed, admitting the elastic fluid to be compressed in a jet superimposed upon said motive fluid jets, and increasing the pressure of the mixture by decreasing its velocity.

14. The method of compressing elastic fluid in a single stage, which consists in expanding elastic motive fluid in superimposed jets overlapping each other in the direction of their flow, isolating the elastic fluid to be compressed from a part of the surface of one of said jets, and admitting the elastic fluid to be compressed in a jet superimposed upon said motive fluid jets, and increasing the pressure of the mixture by decreasing its velocity.

15. The method of compressing elastic fluid in a single stage from an absolute pressure of two inches or less to atmospheric pressure or higher, which consists in producing superimposed jets of motive fluid overlapping each other in the direction of their flow, entraining the elastic fluid to be compressed by one of said jets which separates said elastic fluid to be compressed from another jet, and increasing the pressure of the mixture by decreasing its velocity.

16. The method of compressing elastic

fluid with a total ratio of compression upward of sixty in double stage operation, which consists in producing in each stage superimposed jets of motive fluid overlapping each other in the direction of their flow, entraining the elastic fluid to be compressed by one of said jets which separates said elastic fluid to be compressed from another jet, and increasing the pressure of the mixture by decreasing its velocity.

17. Ejector apparatus comprising an inlet for fluid to be compressed, an inlet for motive fluid, a plurality of closely adjacent annular motive fluid nozzles communicating with said inlet for motive fluid, a diffuser common to said nozzles, and means for conducting the fluid to be compressed from said first named inlet to a passage formed between one of said nozzles and one side of said diffuser.

18. Ejector apparatus comprising an inlet for fluid to be compressed, an inlet for motive fluid, a plurality of closely adjacent annular motive fluid nozzles communicating with said inlet for motive fluid and overlapping each other, a diffuser common to said nozzles, and means for conducting the fluid to be compressed from said first named inlet to a passage formed between one of said nozzles and one side of said diffuser.

19. Ejector apparatus comprising an inlet for fluid to be compressed, an inlet for motive fluid, a plurality of closely adjacent nozzles delivering superimposed jets of motive fluid, a closely adjacent nozzle delivering fluid to be compressed in a jet superimposed upon said motive fluid jets, and a diffuser common to said nozzles and having a wall forming a continuation of a wall of one of said nozzles.

20. Ejector apparatus comprising an inlet for fluid to be compressed, an inlet for motive fluid, a plurality of closely adjacent nozzles delivering superimposed intersecting jets of motive fluid, a closely adjacent nozzle delivering fluid to be compressed in a jet superimposed upon said motive fluid jets, and a diffuser common to said nozzles and having a wall forming a continuation of a wall of one of said nozzles.

21. Ejector apparatus comprising an inlet for fluid to be compressed, an inlet for motive fluid, a plurality of closely adjacent nozzles delivering superimposed jets of motive fluid, a closely adjacent nozzle delivering fluid to be compressed in a jet superimposed upon said motive fluid jets, and a diffuser common to said nozzles, one of said motive fluid nozzles delivering its jet closely adjacent to a wall of said diffuser.

22. Ejector apparatus comprising an inlet for fluid to be compressed, an inlet for motive fluid, a plurality of closely adjacent nozzles delivering superimposed intersecting jets of motive fluid, a closely adjacent nozzle

delivering fluid to be compressed in a jet superimposed upon said motive fluid jets, and a diffuser common to said nozzles, one of said motive fluid nozzles delivering its jet closely adjacent to a wall of said diffuser. 70

23. Ejector apparatus comprising an inlet for fluid to be compressed, an inlet for motive fluid, a plurality of closely adjacent nozzles delivering superimposed jets of motive fluid, a closely adjacent nozzle delivering fluid to be compressed in a jet superimposed upon said motive fluid jets, a diffuser common to said nozzles, and means for adjusting said last named nozzle. 75

24. Ejector apparatus comprising an inlet for fluid to be compressed, an inlet for motive fluid, a plurality of closely adjacent nozzles delivering superimposed jets of motive fluid, a closely adjacent nozzle delivering fluid to be compressed in a jet superimposed upon said motive fluid jets, a diffuser common to said nozzles, and means for adjusting the throat of said last named nozzle. 80

25. Ejector apparatus comprising an inlet for fluid to be compressed, an inlet for motive fluid, a plurality of closely adjacent overlapping nozzles delivering superimposed jets of motive fluid overlapping each other in the direction of their flow, a closely adjacent nozzle delivering fluid to be compressed in a jet superimposed upon said motive fluid jets, and a diffuser common to said nozzles and having a wall forming a continuation of the wall of one of said nozzles. 95

26. Ejector apparatus comprising an inlet for fluid to be compressed, an inlet for motive fluid, a plurality of closely adjacent overlapping nozzles delivering superimposed jets of motive fluid overlapping each other in the direction of their flow, a closely adjacent nozzle delivering fluid to be compressed in a jet superimposed upon said motive fluid jets, and a diffuser common to said nozzles, one of said motive fluid nozzles delivering its jet closely adjacent to a wall of said diffuser. 100

27. Ejector apparatus comprising an annular diffuser and annular nozzle structure associated therewith comprising nozzle members separated from each other to form a nozzle passage, a support for one of said nozzle members having a chamber, said one of said nozzle members having a passage connecting said chamber and the nozzle passage, and a motive fluid chamber in which said support is disposed, said support being perforated to afford communication between said motive fluid chamber and the chamber within said support. 115

28. Ejector apparatus comprising an annular diffuser and annular nozzle structure associated therewith comprising nozzle members separated from each other to form a nozzle passage, a support for one of said 120

- 6 nozzle members having a chamber, the throat of the nozzle formed within said one of said nozzle members and communicating with the chamber in said support, and a motive fluid chamber in which said support is disposed, said support being perforated to afford communication between said motive fluid chamber and the chamber within said support.
- 10 29. Ejector apparatus comprising an annular motive fluid nozzle, an annular diffuser in alignment therewith, a wall of said diffuser being substantially parallel to the jet delivered by said nozzle, another wall of said diffuser being inclined with respect to said first named wall, and a passage for fluid to be compressed to one side of said nozzle and delivering into said diffuser.
- 15 30. Ejector apparatus comprising a plurality of motive fluid nozzles, a nozzle member common to neighboring nozzles, and passages for motive fluid to said nozzles outside of and inside of said nozzle member.
- 20 31. Ejector apparatus comprising an inlet for fluid to be compressed, an inlet for motive fluid, a plurality of annular nozzles receiving motive fluid from said last named inlet, a diffuser common to said nozzles, and an annular member forming communication between said first named inlet and said diffuser.
- 25 32. Ejector apparatus comprising an inlet for fluid to be compressed, an inlet for motive fluid, a plurality of annular nozzles receiving motive fluid from said last named inlet, a diffuser common to said nozzles, an annular member forming communication between said first named inlet and said diffuser, and means for adjusting the position
- 30 33. Ejector apparatus comprising an annular diffuser and coöperating annular nozzles comprising adjacent nozzle members spaced from each other to form nozzle passages, one of said nozzle members being common to neighboring nozzles, and means for adjusting said one of said nozzle members with respect to the neighboring nozzle members.
- 35 34. Ejector apparatus comprising an annular diffuser and coöperating annular nozzles comprising adjacent nozzle members spaced from each other to form nozzle passages, one of said nozzle members being common to neighboring nozzles, and means for adjusting said one of said nozzle members with respect to the neighboring nozzle members, one of said nozzle passages being inclined with respect to a neighboring nozzle passage.
- 40 35. Ejector apparatus comprising an annular diffuser and coöperating annular nozzles comprising adjacent nozzle members spaced from each other to form nozzle passages, one of said nozzle members being

- common to neighboring nozzles, and means for adjusting said one of said nozzle members with respect to the neighboring nozzle members, one of said nozzle passages overlapping a neighboring nozzle passage. 70
36. Nozzle structure comprising a hollow nozzle member, a throat therein, a co-operating nozzle member having a projection extending toward said throat, a third member spaced from said first named member to form a second nozzle, and motive fluid connections with said second nozzle and with the interior of said hollow nozzle member. 75
37. Nozzle structure comprising a hollow nozzle member, a throat therein, a co-operating nozzle member having a projection extending toward said throat, a third member spaced from said first named member to form a second nozzle, motive fluid connections with said second nozzle and with the interior of said hollow nozzle member, and means for adjusting the positions of said nozzle members. 80
38. Radial flow ejector apparatus comprising an annular diffuser, a motive fluid inlet on one side, an inlet for fluid to be compressed on the other side, and a plurality of annular nozzles producing jets of motive fluid between said inlets and discharging into said diffuser. 90
39. Radial flow ejector apparatus comprising an annular diffuser, a motive fluid inlet on one side, an inlet for fluid to be compressed on the other side, a plurality of annular nozzles producing jets of motive fluid between said inlets and discharging into said diffuser, and a passage for fluid to be compressed decreasing in area toward said jets. 95
40. Single stage ejector apparatus for compressing elastic fluid from a pressure corresponding with two inches or less absolute pressure to atmospheric pressure or higher comprising an annular diffuser, a motive fluid inlet on one side, an inlet for fluid to be compressed on the other side, and a plurality of annular nozzles producing jets of motive fluid between said inlets and discharging into said diffuser. 105
41. Multi-stage ejector apparatus comprising in each stage an annular diffuser, a motive fluid inlet on one side, an inlet for fluid to be compressed on the other side, a plurality of annular nozzles producing jets of motive fluid between said inlets and discharging into said diffuser, and a connection from the diffuser of one stage to the inlet for the fluid to be compressed of another stage. 115
42. Ejector apparatus comprising a diffuser and a plurality of motive fluid nozzles discharging into said diffuser, said nozzles comprising members spaced from each other to form nozzle passages, one of said nozzle members being common to neighboring nozzle members. 125

zles, and a nozzle member for one of the nozzle passages forming a continuation of a wall of said diffuser.

43. Ejector apparatus comprising a diffuser and a plurality of nozzles discharging into the same, said nozzles comprising nozzle members spaced from each other to form nozzle passages, one of said nozzle members being common to neighboring nozzle passages, and means for adjusting a plurality of said nozzle members.

44. Ejector apparatus comprising an annular diffuser and coöperating annular nozzles, said nozzles comprising nozzle members spaced from each other to form nozzle passages, one of said nozzle members being common to neighboring nozzles, means for adjusting said one nozzle member, and means for adjusting another of said nozzle members with respect to said one nozzle member.

45. Multi-stage ejector apparatus comprising serially connected ejectors, one of said ejectors comprising an annular dif-

fuser and coöperating annular nozzles, said nozzles comprising nozzle members spaced from each other to form closely adjacent nozzle passages, one of said nozzle members being common to neighboring nozzles.

46. Ejector apparatus comprising an annular diffuser and coöperating annular nozzles, said nozzles comprising nozzle members spaced from each other to form nozzle passages, one of said nozzle members being common to neighboring nozzles, a support for said one of said nozzle members having a chamber and a passage communicating with said chamber and with one of the nozzle passages, and a motive fluid chamber surrounding said support and communicating with another of the nozzle passages and through said chamber in said support with said one of the nozzle passages.

In testimony whereof I have hereunto affixed my signature this 28th day of February, 1917.

ROBERT SUCZEK.
